UNITED STATES PATENT OFFICE.

HOMER T. YARYAN, OF TOLEDO, OHIO.

PROCESS OF AND APPARATUS FOR PURIFYING OXIDIZABLE LIQUIDS.

SPECIFICATION forming part of Letters Patent No. 280,549, dated July 2, 1883.

Application filed March 31, 1883. (No model.)

To all whom it may concern:

Be it known that I, HOMER T. YARYAN, a citizen of the United States, residing at Toledo, Ohio, have invented new and useful Improvements in Processes of and Apparatus for Purifying Oxidizable Liquids, of which the following is a specification.

My invention relates to the manufacture of linseed and other oils by the "solvent" process, in which the oil is extracted by digesting the oil-bearing substance with a liquid solvent, usually a hydrocarbon. In this manufacture it has been usual to treat the oil by aeration at the close, in order to drive off the final traces of the residual solvent; and my invention relates more particularly to this feature of the manufacture, its object being to improve the processes usually employed with respect to the injurious oxidizing effect of the air used; and it consists in the method hereinafter described for deoxidizing the air to a greater or less degree and aerating the oil with such deoxidized air, and also in the apparatus for working such process on a commercial scale in an economical manner.

In the accompanying drawing I have shown an apparatus for carrying out my invention, consisting, substantially, of a furnace, A, air pump or blower B, aerating-tank C, and their connecting-pipes, this apparatus being employed to obtain a deoxidation of the air by combustion of coke or charcoal, producing nitrogen and carbonic acid, in which form the oxygen has a stronger affinity for its associated elements than for the molecules of the oil to be treated.

The furnace may be of any convenient construction, preferably a simple fire-pot inclosing a grate and terminating above in a chimney, a, provided with a cut-off valve, b, (indicated by dotted lines.) Between the valve b and the fire-pot a pipe, c, leads from the uptake a to the blower B, either direct, as indicated by the dotted lines, or through an ordinary wash-box, D, in which the gases are cooled and washed by passage through water intermediate between the furnace A and blower B.

The blower B may be an ordinary rotary

pressure-blower, or any form of air-pump by which the current of air may be drawn through the incandescent fuel and pipe c, and forced forward through the pipe d into a coil, d', arranged in the bottom of the aerating-tank C, whence it is discharged upward through suitable perforations into the contained liquid in the usual manner.

Various modifications of the above-stated method of applying the essential principle of my invention may be employed, such as deoxidizing the air by the use of chemical absorbents; but for practical purposes the method described is found to be most efficient and economical, and is therefore preferred.

The operation is sufficiently obvious. The valve b is left open in starting the fire, after which it is closed, and the products of combustion carried by the action of the blower through the pipes c d and discharged through the coil d'. Where the heat of the gases is not objectionable, the wash-box D may be dispensed with.

I claim as my invention and desire to secure by Letters Patent—

1. The art or process of purifying liquids—such as oils containing residual traces of a hydrocarbon or other vaporizable solvent—consisting in first deoxidizing air, then treating the liquid with such product by the ordinary method of aeration, substantially as set forth.

2. The art or process of purifying oxidizable liquids—such as oils containing residual traces of a hydrocarbon or other vaporizable solvent—by drawing air through incandescent coke, charcoal, &c., and forcing the gaseous product of combustion through the liquid, as in the ordinary process of aeration, substantially as set forth.

3. The art or process of purifying oxidizable liquids—such as oils containing residual traces of a hydrocarbon or other vaporizable solvent—by drawing off the gaseous product of the combustion of coke, charcoal, &c., cleansing and cooling the same by passage through water, thence forcing the same in a finely-divided state through the liquid under treatment, substantially as set forth.

4. The furnace A, blower B, aerating-tank

C, and connecting pipes *c*, *d*, and *d'*, when used in combination as an apparatus for aerating oxidizable liquids, as set forth.

5. The combination of the furnace A, wash-box D, blower or pump B, tank C, and pipes *c d d'*, substantially as and for the purpose set forth.

In testimony whereof I have hereunto set my hand in the presence of two subscribing witnesses.

HOMER T. YARYAN.
